UNITED STATES PATENT OFFICE.

CARL J. SEVERSON, OF MINNEAPOLIS, MINNESOTA.

STORM-SASH FASTENER.

1,055,669.

Specification of Letters Patent. Patented Mar. 11, 1913.

Application filed March 29, 1912. Serial No. 687,189.

To all whom it may concern:

Be it known that I, CARL J. SEVERSON, of Minneapolis, Hennepin county, Minnesota, have invented certain new and useful 5 Improvements in Storm-Sash Fasteners, of which the following is a specification.

The object of my invention is to provide means by which, when the window sash is opened or closed, the storm sash will be 10 correspondingly moved.

A further object is to provide a fastening device designed to be permanently mounted on the storm sash and having means for easily and quickly connecting it with the 15 window sash.

A further object is to provide a fastening device which, when the window sash is closed, will draw the storm sash snugly to its seat, thereby preventing it from shaking 20 or rattling in the wind.

The invention consists generally in various constructions and combinations, all as hereinafter described and particularly pointed out in the claim.

25 In the accompanying drawings forming part of this specification, Figure 1 is a vertical, sectional view through a window frame sash with my invention applied thereto, showing the storm sash in its closed position, Fig. 2 is a similar view, showing the storm sash in its open position, Fig. 3 is a detail side view of the sash fastener, Fig. 4 is a plan view of the same.

In the drawing, 2 represents the window 35 sill, 3 the window frame and 4 the lower sash of the window, all of ordinary construction.

6 is the storm sash, hinged at 7 by any suitable means to the window frame and 40 having the usual beveled edge 8 at its lower end to fit snugly against the inclined surface of the window sill.

Many devices have been employed for operating the storm sash to open or close it 45 when the window sash is raised, but all of them have been more or less objectionable, principally on account of their insecure fastening and the fact that they allow the storm sash to shake and rattle in the wind, 50 and even when closed do not hold it securely. Furthermore, in many devices it is necessary, first, to raise the window sash

and then operate some mechanism for opening or closing the storm sash. The connection which I prefer to employ between 55 the window sash and the storm sash consists of a metal bar 9 having a lug 10 at one end to engage an ear 11 that is fastened to the lower rail of the window sash. The bar 9 is preferably of flat metal and its 60 inner portion is edgewise to the window sash, while its outer portion 12 is twisted into a plane at right angles substantially to the plane of the inner portion and is curved slightly, as indicated in Fig. 3 and provided 65 with an eye 13 at its outer end which engages a second ear 14 mounted on the storm sash.

In placing this device on the window, the parts are adjusted so that the storm sash 70 will contact with its seat before the window sash is entirely closed, and consequently the final closing movement of the window sash will flex the part 12 of the bar 9 and draw the storm sash to its seat with a yielding 75 tension, thereby excluding the cold air and positively preventing the storm sash from rattling in the wind. The hooked end is made to fit snugly on the bar of the ear 11 and the eye at the opposite end of the fastener also fits snugly on the bar of the ear 14 and consequently, even when the storm sash is open, it will be held securely against shaking or rattling.

The fastener will be permanently mounted 85 on the storm sash, one on each side thereof, and when the sash is hung on the window the inner hooked ends will be engaged with the ears on the window sash so that whenever the window sash is raised or lowered a corresponding movement of the storm sash will take place.

I do not wish to be confined to the precise manner of mounting the fastening device illustrated herein or to the shape of 95 the fastening bar, as in various ways the details may be modified and still be within the scope of my invention.

I claim as my invention:—

The combination, with a window frame 100 and a window sash and a storm sash hinged on said frame, of a bar pivotally connected with a side rail of said storm sash and with the lower rail of said window sash, said bar

having a curved, flexible portion, the distance between the pivots of said bar on said sashes increasing with the closing of the window sash, whereby said curved flexible portion will be put under tension when the window sash is closed to hold the storm sash snugly on its seat.

In witness whereof, I have hereunto set my hand this 26th day of March, 1912.

CARL J. SEVERSON.
